UNITED STATES PATENT OFFICE.

ERNEST E. ASPINWALL, OF PAWTUCKET, RHODE ISLAND.

MACHINE FOR GLAZING AND FINISHING YARNS, THREADS, AND TWINES.

1,212,877.

Specification of Letters Patent. Patented Jan. 16, 1917.

Application filed October 21, 1915. Serial No. 57,076.

To all whom it may concern:

Be it known that I, ERNEST E. ASPINWALL, a citizen of the United States, residing at Pawtucket, in the county of Providence and State of Rhode Island, have invented a new and useful Improvement in Machines for Glazing and Finishing Yarns, Threads, and Twines, of which the following is a specification.

10 This invention relates to certain new and useful improvements in machines for glazing and finishing yarns, threads and twines, and it purposed to provide a machine which will operate efficiently in applying size or 15 finish to yarn, drying and glazing or otherwise finishing the surface of the yarn subsequent to the application of the size.

The invention further resides in forming the lower size or squeeze rolls hollow and 20 heating the same to keep the sizing constantly warm.

Another object of the invention is to provide a brush roll rotating reversely to the 25 traverse of the yarn for acting upon the latter.

Other aims will be hereinafter set forth and claimed, the preferred embodiment of the invention being depicted in the drawings wherein—

30 Figures 1 and 1^a show the machine from one side and in elevation. Figs. 2 and 2^a depict the machine in elevation from the opposite side thereof.

Referring now to Figs. 1, 1^a, 2, and 2^a, the 35 immersion rolls 4 and 16 are pivotally connected, respectively to vertically movable rack members 30 and 30' by links 31, the latter being joined at their top portions by a rod 32, the rack members 30 and 30' being 40 slidably disposed in brackets 33 in which are journaled drive pinions 34. These pinions mesh with the rack portion of members 30 and 30' and are rotatable by cranks 35. The immersion rolls slide in the respective 45 guides 5—17 and are to direct and immerse the yarn in the size or finish while the machine is in operation. When the machine is idle, these rolls are elevated from the box so that the yarn will not absorb or collect 50 an excess of the size or finish and render it harsh or stiff. By inclining the guides the immersion rolls are lowered in proximity to and beneath the size rolls where they combinedly agitate the size or finish. The dis- 55 position of these guides permits of the immersion rolls being held against vibratory

or swinging movements and, further, provides sufficient space between the rolls and rack members to enable the operative to work about the machine with facility. 60

The lower size or squeeze rolls 7 and 19 are hollow for the circulation of steam there-through. Steam is admitted axially through pipe 36 on one side of the machine and escapes from the opposite side through pipe 65 37. Between a pipe 36 and its size roll is a sprocket 38, while a suitable stuffing box 39 is employed to eliminate leakage of the size from the size box.

The size rolls are arranged within the 70 size boxes to remove by pressure or to squeeze from the yarns all surplus size or finish, the top rolls 8 and 20 being covered with a cloth to form a soft cushion to aid in the squeezing. Normally, the top size 75 roll is heavy enough to remove all surplus- age when a light finish is used. However, for a heavy finish additional pressure is obtained by a pair of weighted levers 40 pivoted to the main frame 41, as at 42. The 80 main frame is provided with seats 8' and 20' in which the top size rolls are engaged when inoperative so as to keep the rolls away from the yarns which will hang in suspense and remain free from contact with wet size rolls. 85

The size and finish in the boxes 6 and 18 are kept above a certain temperature in order to keep the material in liquid form so that the same will penetrate into and cause it to adhere more firmly to the yarn. 90 The heat necessary for maintaining the size and finish in liquid form is supplied by means of steam and hot water. Furthermore, this supplied heat is necessary to assist the evaporation of the moisture in the 95 size and finish since moisture is more easily evaporated when warm than cold.

The wipers which are arranged to the rear of the size rolls remove any and all surplus size and finish as well as lay the fiber onto 100 the yarns during movement of the latter and by means of pressure. Each wiper com- 105 prises a fixed strip-like element 9—21, and an adjustable element 10—22, said elements having angular end flanges or extensions bolted to the upper bars of the frame, the adjustable element being slidably mounted on the main frame through pin and slot con- 110 nections 43, as depicted in Fig. 1. The op- posing surfaces of the wiper elements are soft and brought together so as to encompass the yarn to cause the fibers to be drawn back

and embedded into the size and finish. The wiper elements are separable for passing the yarns therebetween.

Subsequent to passing between or through the wipers, the yarn is separated by the scored rolls 12 and 23 which are journaled in brackets or arms 44 adjustably mounted on arched supports 45. These supports are arranged on the main frame at the ends of the rotary brushes and each comprises a flat, strip-like, arcuate body having radial foot portions extending in opposite directions from its ends for being secured to the upper horizontal bars of frame 41. This arrangement enables the journaling of the brushes on the frame bars concentric with the arched supports 45. The rolls 13—25—14 and 26 are likewise adjustably supported from the arched supports by the brackets 46 and 47 which are adjustable circumferentially of the brushes in spaced arcuate slots formed in each of said supports. By adjusting these rolls at greater or lesser angles, more or less contact with the brushes is afforded.

The circular brushes 11—24 which are designed to polish the yarns, are revolved in opposite direction to the traverse of the latter. The main frame is provided with panels (not shown) for forming an inclosure or chamber in which are located the steam pipes 48, the latter supplying heat to warm the brushes to thereby further effect evaporation of moisture in the size or finish on the yarn.

Steam pipes 36 and 48 are suitably connected to a source not here shown. The tension rolls 27 are disposed in vertical slots 50 of standards 51 and are driven to draw the yarns from and into the brush so as to create a tension and friction on the latter such as is necessary to polish or glaze the finish and thus eliminate "back lashing" on the brush which revolves in the opposite direction. These rolls are covered with a soft cushion to afford a better grip and avoid friction and chafing therebetween.

In instances where two sets of size rolls are employed such as is illustrated, the second set of rolls 19—20 are driven to serve the purpose of tension rolls.

The brushes are driven from a source of power by the belt P and pulley P' mounted on the shaft of the brush frame 11', a sprocket 55 being secured to the opposite end of said shaft over which passes the chain 54 to the sprocket 55', causing rotation of the brush frame 24' and the sprocket 58 causing rotation of the sprocket 53 by means of the chain 53'. The shaft of the sprocket 53 passes across the end of the machine and carries at one side the pulley 52 which causes rotation of the pulley 52' by reason of the connecting belt, the pulley 52' in turn causing rotation of the rolls 27 by reason of the belt 56, pulley 56' and pulley 56''. On the opposite end of the shaft of the sprocket 53 is secured the gear 59 which is in mesh with the gear 60 which drives the chain 57, causing rotation of the sprockets 38—38 and the squeeze rolls 7—19. Suitable tension is applied to the chain 57 by the roll 61.

In some instances speed changing gearing (not shown) will be employed for obvious reasons.

Throughout the specification and claims, the word "yarns" is used to signify also threads and twines.

Having thus described my invention, what I claim as new and desire to secure by Letters Patent is—

In a machine of the character described, a frame having spaced upper bars, arcuate strip-like supports having inwardly and outwardly extending radial foot-portions on their ends secured to the frame bars, each support being provided with a series of circumferentially spaced arc-shaped slots, independently adjustable brackets secured in the support slots in radial disposition, rollers supported by the brackets, and a brush journaled on the frame bars between the foot portions of the arcuate supports and in concentric relation with the latter.

In testimony whereof I have signed my name to this specification in the presence of two subscribing witnesses.

ERNEST E. ASPINWALL.
